Primary Examiner — Stacia A Cadmus(74) *Attorney, Agent, or Firm* — Arent Fox LLP(57) **CLAIM**

The ornamental design for a wheel, as shown and described.

DESCRIPTION

FIG. 1 is a front right perspective view of a wheel showing our new design;

FIG. 2 is a rear left perspective view of the design shown in FIG. 1;

FIG. 3 is a front view of the design shown in FIG. 1;

FIG. 4 is a rear view of the design shown in FIG. 1;

FIG. 5 is a left side view of the design shown in FIG. 1;

FIG. 6 is a right side view of the design shown in FIG. 1;

FIG. 7 is a top view of the design shown in FIG. 1; and,

FIG. 8 is a bottom view of the design shown in FIG. 1; The broken lines shown in the figures are included for the purpose of illustrating portions of the wheel and form no part of the claimed design.

1 Claim, 8 Drawing Sheets(56)
